UNITED STATES PATENT OFFICE.

HARRY C. EDWARDS AND JOHN T. MEGREDY, OF KANSAS CITY, MISSOURI.

AUTOMOBILE-JACK.

1,137,003.

Specification of Letters Patent. Patented Apr. 27, 1915.

Application filed September 21, 1914. Serial No. 862,709.

To all whom it may concern:

Be it known that we, HARRY C. EDWARDS and JOHN T. MEGREDY, citizens of the United States, residing at Kansas City, in the county of Jackson and State of Missouri, have invented certain new and useful Improvements in Automobile-Jacks, of which the following is a specification.

This invention relates to automobile jacks of that class whereby a single operator is enabled to easily and quickly lift or "jack-up" an automobile, and the object is to produce an efficient "jack" embodying the desirable features of simplicity, durability and cheapness of construction and installation.

To this end the invention consists in certain novel and peculiar features of construction and organization as hereinafter described and claimed; and in order that it may be fully understood, reference is to be had to the accompanying drawing, in which—

Figure 1, is a side elevation of an automobile jack embodying the invention. Fig. 2, is a top plan view, partly broken away, of a part of the jack. Fig. 3, is a rear end view of the jack. Fig. 4, is a side view of a portion of a slightly modified form of the jack, 30 a shaft thereof being shown in section.

In the said drawing 1 indicates a pair of parallel angle irons adapted to be secured rigidly to the floor of a garage, in any suitable manner, and each angle iron preferably 35 consists of two sections bolted together at 2, so that the length of the bed frame constituted by the angle irons, may be increased or diminished to accommodate the size of the car or the garage. Secured rigidly to 40 and projecting upwardly from the said bed frame near the opposite ends of each angle iron or side thereof, are standards 3, and arranged adjacent and at the inner sides of and supported from said standards are journaled rollers 4.

A lifting frame of rectangular form comprises side rails 5 of angle iron and end bars 6, connecting the ends of rails 5, the end bars 6 being of "dropped" form to enable the differential housing of an automobile, to pass 50 over them when the car is run on or off the jack, and this lifting frame will preferably be made in sections adjustably connected together so that the cam bars 7 secured to the 55 rails 5 by bolts 8, shall be disposed the proper distance apart to coöperate with

rollers 4 in raising or lowering the car without tilting it; it being noted by reference to Figs. 1 and 3 particularly, that the wheels 4 and cam bars 7 are disposed in superposed relations, and that when the lift frame is in normal position, the high ends of the cam surfaces of said bars 7 are resting on the said rollers. In Fig. 4, the cam bars (one only appearing) are shown as provided 65 with teeth 9 along their cam surfaces, for a purpose which hereinafter appears.

Referring now to the lift-frame operating mechanism, 10 is a shaft extending transversely of and over the bed-frame at a suitable point between the front and rear pairs of rollers 4, and journaled in bearing standards 11 rigidly secured in any suitable manner to rails 1, and in a third bearing standard, 12, disposed a considerable distance 70 outward from the bed-frame; said shaft between the bearing standard 12 and the bed-frame being provided with a crank 13 which, when the lift-frame is lowered or in normal position as shown, rests upon the 75 floor of the garage so that the wheels of a car can run over it. The upper half of standard 12 is semi-circular in contour and peripherally formed with ratchet teeth 14 for engagement by a latch 15 carried by a 80 lever 16, the lever also carrying a pivoted grip 17 connected by a rod 18 with the latch for the purpose of disengaging the same from a ratchet tooth 14, it being preferred that the latch shall be of the ordinary 85 spring-actuated type, the spring being hidden in the casing of the latch.

Secured rigidly on shaft 10 is a pair of sprocket wheels 19, connected by chains 20 with pull rods 21 secured at their rear ends 95 on the rearmost bolts 8, by retaining nuts 22.

In Fig. 4, smooth-tread rollers are replaced by peripherally toothed rollers adapted for engagement with cam bars 7 as a pinion engaging a rack bar. In this construction the rearmost pair of rollers will be mounted on shaft 10 which will be transferred in position to said rollers, together with bearing 12 and the parts composing the latch mechanism, the sprocket wheels 19, 100 chains 20 and rods 21 being dispensed with.

Assuming that a car is run over the jack and stopped in position shown by the dotted wheels, in Figs. 1 and 3, it will be seen that the car can be readily jacked-up by swinging the lever 16 in the direction indicated by the arrow, Fig. 1, as by this action shaft

10 is turned and through the pull connection described, imparts forward movement to the lift-frame, the lift-frame also moving upward through the travel of the cam bars 5 on the rollers. The lift-frame, in moving upward, encounters the axles of the car and lifts the same bodily from the floor. For cars having straight rear axles arranged slightly higher than the front axles of such 10 cars, the pitch of the rear cam bars may be increased sufficiently to raise the rear end of the lift-frame enough higher than the front end to simultaneously engage both axles and raise the car without disturbing the horizontalism of the same. The latch mechanism guards against back rotation of the shaft 10 until manually tripped, upon which occurrence the lift-frame will travel downward and rearward upon the rollers to normal position, this action of course lowering the car until its wheels again rest upon the floor. The operation in connection with the construction shown by Fig. 4, is identical with that described.

25 From the above description it will be apparent that we have produced an automobile jack embodying the features of advantage enumerated as desirable and which may be modified in minor particulars as regards its 30 form, proportion, detail construction and organization of parts, without departing from the spirit and scope of the appended claims.

We claim:

35 1. An automobile jack, comprising two pairs of journaled rollers, a frame provided with cam bars for operation on said rollers to effect a variation in the altitude of the frame, a suitably journaled shaft extending 40 transversely of and below the said frame, and provided at one side of the latter with a crank adapted to occupy a substantially floor-level position when the said frame is in

normal or lowered position, so that the wheels of a motor car may roll over without injuring the said crank, connections between said shaft and said frame whereby rotation of the former shall effect endwise movement of the frame and the consequent raising thereof through the co-operative action of the 50 cams and rollers, and means for operating the shaft.

2. An automobile jack comprising two pairs of journaled rollers, a frame provided with cam bars for operation on said rollers, a suitably-journaled shaft extending transversely of and below said frame, provided at one side of the latter with a crank adapted when vertically pendant to contact with the floor, a lever secured to the shaft outward of the crank, means whereby the operation of said lever effects climbing movement of the cam bars on said rollers, and latch mechanism to secure the lever in adjusted position.

3. An automobile jack comprising two pairs of journaled rollers, a frame provided with cam bars for operation on said rollers, a suitably-journaled shaft extending transversely of and below said frame, provided at one side of the latter with a crank adapted when vertically pendant to contact with the floor, a pair of sprocket wheels secured on said shaft, chains engaging the wheels and connected to said frame, a lever secured to the shaft outward of said crank, and latch mechanism to secure the lever in adjusted position.

In testimony whereof, we affix our signatures, in the presence of two witnesses.

HARRY C. EDWARDS.
JOHN T. MEGREDY.
